US00D757678S

(12) **United States Design Patent**
Kelly et al.

(10) **Patent No.:** US D757,678 S
(45) **Date of Patent:** ** May 31, 2016

(54) **PORTABLE SPEAKER**

(71) Applicant: **Skullcandy, Inc.**, Park City, UT (US)

(72) Inventors: **Peter M. Kelly**, Park City, UT (US);
David G. Vogt, Jr., Salt Lake city, UT (US);
Donald C. Stiff, Portland, OR (US);
Lucas Wright-Moore, Salt Lake City, UT (US)

(73) Assignee: **Skullcandy, Inc.**, Park City, UT (US)

(**) Term: **14 Years**

(21) Appl. No.: **29/497,633**

(22) Filed: **Jul. 25, 2014**

(51) **LOC (10) Cl.** 14-01

(52) **U.S. Cl.**

USPC **D14/204**

(58) **Field of Classification Search**

(57) **CLAIM**

The ornamental design for a portable speaker, as shown and described.

DESCRIPTION

FIG. 1 is a perspective view of a portable speaker, showing our new design.

FIG. 2 is a top plan view of the portable speaker shown in FIG. 1.

FIG. 3 is a bottom plan view of the portable speaker shown in FIG. 1.

FIG. 4 is a left side view of the portable speaker shown in FIG. 1.

FIG. 5 is a right side view of the portable speaker shown in FIG. 1.

FIG. 6 is a back view of the portable speaker shown in FIG. 1; and,

FIG. 7 is a front view of the portable speaker shown in FIG. 1. The broken line portions of FIGS. 1-7 are included to show unclaimed subject matter only and form no part of the claimed design.

1 Claim, 3 Drawing Sheets
